The ornamental design for an auxiliary device for washing machine, as shown and described.

DESCRIPTION

FIG. 1 is a front perspective view of an auxiliary device for washing machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective reference view thereof, in which two components of the auxiliary device for washing machine are in a slid out position from the auxiliary device for washing machine;

FIG. 9 is another perspective reference view thereof, in which one component of the auxiliary device for washing machine is in a slid out position from the auxiliary device for washing machine; and,

FIG. 10 is a front reference view thereof, in which the auxiliary device for washing machine is applied to a washing machine.

The broken lines illustrating portions of the auxiliary device for washing machine and portions of the article form no part of the claimed design.
